REAMER

Wiley B. Noble, Houston, Tex., assignor to Reed
Roller Bit Company, Houston, Tex., a corpora-
tion of Texas

Application November 23, 1940, Serial No. 366,817

6 Claims. (Cl. 255—73)

This invention relates to reamers and has particular reference to that type of reamer adapted to be placed in a drilling string above the usual drill bit for drilling a well hole.

It is an object of this invention to provide such a reamer in which the reamer cutters may be readily removed and replaced.

Another object is to provide such a structure in which the removal and replacement of the cutters will not necessitate the use of any special tools whatever.

A further object is to provide a structure in which no bolts or threaded parts are required.

A still further object is to provide such a structure which will be so sure in its operation that the reamer cutters will be firmly and rigidly mounted upon the reamer body and will not become loosened or lost in use, but in which they may be easily and quickly removed and replaced.

Other objects and advantages of this invention will become apparent from the following description taken in connection with the accompanying drawing wherein one embodiment of this invention is illustrated.

In the drawing:

Fig. 1 is a side elevation of a reamer constructed with this invention.

Fig. 2 is a partial longitudinal cross section through the body of the reamer shown in Fig. 1 taken along the axis of one of the reamer cutters and showing the means for mounting the same on the reamer body.

Fig. 3 is a transverse cross section through the structure shown in Fig. 1 taken along the line 3—3 of Fig. 1.

Fig. 4 is a transverse section through the structure shown in Fig. 1 taken along the line 4—4 of Fig. 1.

The body 1 of the reamer shown in the drawing is provided with a plurality of circumferentially spaced major recesses 2, each of which has an auxiliary recess 3 adjacent its lower end and a secondary auxiliary recess 4 adjacent its upper end, these auxiliary recesses opening into the major recess.

Each of the auxiliary recesses 3 and 4 has adjacent the major recess a portion of trapezoidal cross section. The auxiliary recess 3 also has a portion more remote from the major recess which is not a trapezoidal cross section but which is of a width substantially equal to the widest dimension of that portion which is of trapezoidal cross section.

This reamer is provided with three roller cutters 5, each mounted in one of the major recesses 2. 55

Each of these cutters is carried on a bearing shaft 6, which in the example shown is made integral with a supporting block 7 in the lower auxiliary recess. The upper end of each such shaft 6 is carried in a second supporting block 8 mounted in the upper auxiliary recess 4. These supporting blocks are located properly with respect to the major recess by means of pins 9 extending through transverse openings 10 in the body of the reamer. These openings intersect the auxiliary recesses respectively as shown.

For the purpose of locking the respective supporting blocks in place within the reamer body, each of these blocks is bifurcated to provide a wedge-shaped opening on its end remote from the cutter. Received in this opening in each of the blocks is a wedge 11, which when driven home serves to spread the prongs of the bifurcated portion of each block and wedge it tightly in place.

At the same time, each of these wedges is provided on its nose with a slot 12 of a width adapted to straddle a reduced intermediate portion 13 of one of the pins 9. Thus, when the wedge 11 is in place the pin 9 which cooperates with the same supporting block cannot be withdrawn. After the wedges 11 are driven home by means of a hammer or the like, they are secured in place by means of a pair of projections 14 of relatively small cross section on each of the bifurcated parts of the respective supporting blocks. These portions 14 are bent inwardly around the bases of the respective wedges so as to prevent them from coming out.

In mounting the reamer cutter in the reamer body in accordance with this invention, the upper supporting block 8 will first be put in place by inserting it through the major recess 2 into the lower portion of the upper auxiliary recess 4. The cutter 5 will then be put in place in the major recess and the lower supporting block 7 inserted through the lower portion of the lower auxiliary recess 3. When in this position the shaft 6 will extend upwardly into the major recess and the lower block and shaft may then be pushed upwardly through the cutter 5 until the upper end of the shaft fits into the upper supporting block 8, as shown in Fig. 2. The pins 9 are now put in position and the wedges 11 driven into the wedge-shaped openings in the respective supporting blocks 7 and 8, after which the portions 14 will be bent inwardly behind the wedges to hold them in place.

It will be seen from the foregoing that by the structure just described there is provided a means whereby a reamer cutter may be firmly and

rigidly mounted in a reamer body in such a manner that it cannot be readily displaced therefrom in use nor can it become loosened so as to impair the action of the reamer. At the same time it will be readily observed that such cutter can be mounted in the reamer body and removed therefrom at will with no special tools and without the necessity for even such tools as wrenches or the like. There is no threaded part and nothing which can be readily damaged in handling to such an extent that it cannot be used.

Having described my invention, I claim:

1. In a well forming tool, a body having a recess in its surface for a cutter, a cutter in said recess, means for supporting said cutter including cooperating wedge and bifurcated elements, the wedge element lying between the prongs of the bifurcated element, said elements being adapted to be driven relatively to each other to force the prongs of the bifurcated element into frictional engagement with the walls of the recess, deformable means carried by one of said elements adapted to be deformed into blocking engagement with the other element to retain said elements in assembled relation, and a pin extending through the walls of the recess and through one of said elements to anchor the latter, said pin having a portion of reduced diameter intermediate its ends and the other of said elements having a notch in its end adapted, when in assembled position with the anchored element, to receive the reduced portion of said pin to retain the pin in position.

2. In a well forming tool, a body having a recess in its surface for a cutter, a cutter in said recess, means for supporting said cutter including cooperating wedge and bifurcated elements, the wedge element lying between the prongs of the bifurcated element, said elements being adapted to be driven relatively to each other to force the prongs of the bifurcated element into frictional engagement with the walls of the recess, a pin extending through the walls of the recess and through one of said elements to anchor the latter, said pin having a portion of reduced diameter intermediate its ends and the other of said elements having a notch in its end adapted, when in assembled position with the anchored element, to receive the reduced portion of said pin to retain the pin in position, and means for retaining said elements in assembled position.

3. In a reamer of the character described, a body having a plurality of circumferentially spaced longitudinally extending recesses in its outer surface, a cutter in each recess intermediate the ends thereof, a pair of bifurcated elements in each recess one adjacent each end of the cutter, the width of said bifurcated elements being substantially equal to the width of said recess, a wedge element between the prongs of each bifurcated element, the bifurcated and wedge elements at each end of each cutter being adapted to be forced together to spread the prongs of the bifurcated element into frictional engagement with the walls of the recess, means for mounting each end of the cutter on one of the two assembled elements at each end thereof, a pin extending transversely through the walls of the recesses at each end of each cutter and passing through one of the two assembled elements in the recess at each end of the cutter, said pin having a portion of reduced cross section and the other of said two assembled elements having a notch to receive the portion of the pin of reduced cross section to prevent axial displacement of the pin, and deformable extensions on the free ends of the prongs of said bifurcated elements for retaining the bifurcated and wedge elements at each end of the cutter in assembled relation.

4. In a reamer of the character described, a body having a plurality of circumferentially spaced longitudinally extending recesses in its outer surface, a cutter in each recess intermediate the ends thereof, a pair of bifurcated elements in each recess one adjacent each end of the cutter, the width of said bifurcated elements being substantially equal to the width of said recess, a wedge element between the prongs of each bifurcated element, the bifurcated and wedge elements at each end of each cutter being adapted to be forced together to spread the prongs of the bifurcated element into frictional engagement with the walls of the recess, means for mounting each end of the cutter on one of the two assembled elements at each end thereof, a pin extending transversely through the walls of the recesses at each end of each cutter and passing through one of the two assembled elements in the recess at each end of the cutter, said pin having a portion of reduced cross section and the other of said two assembled elements having a notch to receive the portion of the pin of reduced cross section to prevent axial displacement of the pin, and deformable means for retaining said elements in assembled relation.

5. In a reamer of the character described, a body having a plurality of circumferentially spaced longitudinally extending recesses in its outer surface, a cutter in each recess intermediate the ends thereof, a pair of bifurcated elements in each recess one adjacent each end of the cutter, the width of said bifurcated elements being substantially equal to the width of said recess, a wedge element between the prongs of each bifurcated element, the bifurcated and wedge elements at each end of each cutter being adapted to be forced together to spread the prongs of the bifurcated element into frictional engagement with the walls of the recess, means for mounting each end of the cutter on one of the two assembled elements at each end thereof, a pin extending transversely through the walls of the recesses at each end of each cutter and passing through one of the two assembled elements in the recess at each end of the cutter, said pin having a portion of reduced cross section and the other of said two assembled elements having a notch to receive the portion of the pin of reduced cross section to prevent axial displacement of the pin, and deformable means for retaining the bifurcated and wedge elements at each end of the cutter in assembled relation.

6. In a reamer of the character described, a body having a plurality of circumferentially spaced longitudinally extending recesses in its outer surface, a cutter in each recess intermediate the ends thereof, a pair of bifurcated elements in each recess one adjacent each end of the cutter, the width of said bifurcated elements being substantially equal to the width of said recess, a wedge element between the prongs of each bifurcated element, the bifurcated and wedge elements at each end of each cutter being adapted to be forced together to spread the prongs of the bifurcated element into frictional engagement with the walls of the recess, a shaft extending between the pair of bifurcated elements in each recess for mounting said cutter, deformable extensions on the free ends of the prongs

of said bifurcated elements for retaining the bifurcated and wedge elements at each end of the cutter in assembled relation, and a pin extending transversely through the walls of the recess at each end of the cutter and through the prongs of the bifurcated element, said pin having a portion of modified cross section, each

wedge element having a portion adapted to cooperate with the portion of the pin of modified cross section to prevent axial displacement of the pin when the elements are in assembled position.
